UNITED STATES PATENT OFFICE.

JOHN I. BELLAMY, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed July 8, 1921, Serial No. 483,117. Renewed February 4, 1926.

The present invention relates to automatic telephone systems in general, but is concerned more particularly with such systems as include small community automatic exchanges which include party lines and which are connected with the main exchange by trunk lines, although some of the features are not confined thereto; and the principal object, broadly stated, is the production of new and improved circuit arrangements whereby the usual small group of incoming connectors in which the main exchange trunk lines terminate is entirely dispensed with, and the said trunk lines are given access through the medium of rotary trunk selecting switches to the local connectors which are used for setting up local connections within the C. A. X.

To explain the object somewhat more fully, it is common practice, when an automatic connector switch is used by an operator in extending connection to a called subscriber, to arrange the said connector to reverse the incoming trunk conductors when the called subscriber answers, so as to give the calling operator answering supervision. However, if such a connector is used in a system of the type disclosed herein, when a subscriber calls another subscriber on the same line, the line relays of the connector switch are locked up in series with the windings of the back bridge relay when the incoming trunk conductors are reversed. In order to eliminate this difficulty, it has been the usual practice heretofore to provide two groups of connectors. One group, termed incoming connectors, is used by the operator only and is arranged to give so called reversed battery supervision when the called man answers. The connectors of the other group are used by the subscribers only and do not give reversed battery supervision. This arrangement, while obviously satisfactory from some standpoints, is very uneconomical in that each of the two groups of connectors, and especially the group of incoming connectors which is the smaller of the two, is very inefficient owing to the small number of switches therein. As pointed out before, the only difficulty encountered when the connectors used by the subscribers reverse battery upon the answering of the called man, is when a subscriber calls another subscriber on the same line. Accordingly, a special object of the invention is to

provide means whereby a connector switch reverses battery in all cases when the called subscriber answers, except when the called subscriber is on the same line as that of the calling subscriber, thus allowing the two small inefficient groups of connectors to be combined into one larger and more efficient group.

Other objects not specifically mentioned now will become apparent from a further perusal of the specification and will be pointed out in the appended claims.

Referring now to the drawings comprising Figs. 1 and 2 the apparatus shown on the left hand end of sheet 1 is located in a manual exchange which is connected with a small automatic exchange by means of a group of two way trunk lines of which the trunk line comprising conductors 11 and 12 is one.

The remainder of the equipment shown on sheet 1, as well as the switching apparatus shown on sheet 2, is in the automatic exchange.

Referring now particularly to Fig. 1, the trunk line comprising conductors 11 and 12 terminates in the manual exchange in the jack J with which there is associated the visual supervisory signal 2 and the drop 3. The key K is a combination calling device and ringing key which, when thrown in one direction, inserts the common calling device S into the circuit, and when thrown in the other direction places the circuit in condition for ringing a called subscriber, as will be explained fully hereinafter.

Relay 5, associated with the jack J, in addition to the usual core, heel piece, and armature, has a permanent magnet secured to the heel piece at one end and joined to the core at the other end through the medium of a soft iron yoke, as shown. This combination makes a very desirable polarized relay owing to its extremely simple principle of operation. With no current flowing thru the winding, the armature is not attracted owing to the fact that the connecting yoke, core, and heel piece form a magnetic shunt around the permanent magnet. When a current flows in the winding of the relay in such a direction as to generate flux that is the same in direction as that which is normally shunted away from the armature, the armature is still not attracted owing to the fact that not only the core but also the permanent

magnet acts as a shunt, each for the other. When a current is sent through the winding in the opposite direction, however, the magnetic flux passes through the permanent magnet and the core in parallel and returns through the heel piece and armature in series, thus causing the armature to be attracted.

The trunk line comprising conductors 11 and 12 terminates in the automatic exchange in the line switch designated by the reference character C'. This line switch, as well as the line switch C, is of the well known rotary type in which the wipers have no normal position and move in a forward direction only and, in common with the other line switches of the exchange, has access to a plurality of connector switches such as connector H.

The connector H, which mechanically is of the vertical and rotary type and has its bank contacts arranged in horizontal rows or levels, is used by the operator in the manual exchange in extending calls from subscribers whose lines terminate in the said manual exchange, to subscribers whose lines terminate in the automatic exchange and, when seized by a subscriber's line switch such as the line switch C in which the subscriber's line comprising conductors 173 and 175 terminates, is used for extending a connection to the manual exchange or to other subscribers whose lines terminate in the same exchange, including other subscribers on the same line as that of the calling subscriber.

The substation A, which is bridged across the line comprising conductors 173 and 175, is an automatic substation having the usual talking and signalling instrumentalities and also a calling device S' for controlling the automatic switches. In addition, there is provided a push button P, together with the resistance R^o, for the purpose of controlling the ringing relay in a connector switch after a number has been dialled. The resistance R^o, which is normally shunted by a pair of contacts in the calling device S', is inserted in the bridge across the line conductors whenever a number is being dialled. The substation A', which is similar to the substation A, is equipped with a resistance R^s similar to the resistance R^o of substation A, with the exception that it is lower. The substation A², however, which is otherwise similar to the substations A and A', has no resistance corresponding to the resistances R^o and R^s for the reason that it is bridged across the end of a long line equal in resistance to the longest line in the system.

The reason for adding the resistances R^o and R^s to the substations A and A' is to bring the resistance of each subscriber's loop, while the impulses are being sent, up to one standard resistance, which is determined by the resistance of the longest line connected

in the system. By this means all the impulses delivered to the exchange switches are of the same strength regardless of whether the substation from which they are being sent is within a few blocks of the exchange or several miles away. The resistance R, associated with the operator's calling device S, it may be stated, performs a similar function when the operator in the manual exchange is making an automatic call.

The system, having been described more or less in general, will now be described in connection with a detailed description of the operation of the apparatus contained therein. For this purpose it will be assumed that the operator in the manual exchange is extending a connection from a subscriber whose line terminates in the said exchange to the subscriber at substation A, whose line terminates in the automatic exchange. In order to extend the said connection, the operator inserts the other plug of the cord circuit in use into the jack J, thereby operating the tip spring of the said jack so as to disconnect the winding of the drop 3, at the same time placing the spring 4 into engagement with its working contact, thereby closing the following bridge across the conductors 11 and 12: From conductor 12, by way of the normally closed contacts controlled by spring 8 of key K, impedance 6, winding of polarized relay 5, spring 4 and its working contact, normally closed contacts controlled by spring 7, and the normally closed contact controlled by spring 9, to conductor 11. The conductors 11 and 12 are connected to ground and battery, respectively, in the automatic exchange in series with the line relay 14 of the line switch C'. Accordingly line relay 14 energizes in response to the closure of the previously traced bridge; and, upon so doing, closes, at armature 20, a circuit for switching relay 30 and stepping magnet 15 in series; and, at armature 19, connects the test wiper 22 to a point between the winding of relay 30 and the winding of stepping magnet 15. From this point the operation depends upon whether the trunk line, upon which the wipers 21-23, inclusive, are standing, is busy or idle. If it is busy there is a ground potential on the release trunk conductor thereof and consequently on test wiper 22; switching relay 30 is short circuited; and stepping magnet 15, which interrupts its own circuit, operates in the manner of a buzzer to advance the switch wipers step by step in search of an idle trunk line. In the present case, however, we may assume that the trunk line, upon which the wipers of the line switch are standing, is idle when the call is initiated. That being the case, switching relay 30 is not short circuited and stepping magnet 15 is not operated because of the high resistance

of the said relay. Relay 30, however, energizes and at armature 17 places a ground potential on test wiper 22 so as make the seized trunk busy immediately, and at armatures 16 and 18 disconnects the line conductors 11 and 12 from the winding of line relay 14 and ground, respectively, and extends them by way of wipers 21 and 23, bank contacts 24 and 26, trunk conductors 27 and 29, normally closed contacts controlled by armatures 120 and 121, to battery and ground, respectively, by way of the windings of line relays 104 and 102. Line relays 102 and 104 immediately energize over the bridge across conductors 11 and 12 in the manual exchange. Line relay 102, upon energizing, closes at armature 125 a circuit for release relay 103. Upon energizing, release relay 103 prepares a circuit for the vertical magnet at armature 127 and at armature 128 grounds the release trunk conductor 28 by way of the resting contact of armature 143 and said armature. By means of this ground potential on test contact 25 and its multiples in the banks of the other line switches, the connector H is maintained busy in the usual manner. This ground potential extends also by way of test wiper 22 and armature 17 and its working contacts to switching relay 30 thus establishing a holding circuit for said relay before the slow acting line relay 14 has had time to deenergize. A branch of this holding circuit extends by way of private normal conductor 13 to multiple test contacts in the banks of the connector switches, thereby guarding the calling trunk line against intrusion in the usual manner.

Returning now to the polarized relay 5, the winding of which is included in the bridge across conductors 11 and 12, the said relay is energized at this time owing to the fact that the flux generated in the core is parallel in direction to that emanating from the associated permanent magnet and consequently a magnetic circuit is set up through the said magnet and core in parallel and the heel piece and armature in series resulting in the attraction of the armature. The said armature, upon being attracted, places the visual supervisory signal 2 in multiple with the lower trunk conductor and the line relay 102 of the connector H, whereupon the said supervisory signal becomes energized.

The operator may now throw her key K to calling position, whereupon springs 7 and 8, upon being operated, remove the polarized relay 5 and impedance 6 from the bridge across conductors 11 and 12 and insert the common calling device S, together with its resistance R, therein. Polarized relay 5 and the visual signal 2 now become deenergized. As has been mentioned before, the resistance of R is just high enough to bring the re-

sistance of the calling trunk line up to the resistance of the longest line included in the system.

The operator may now manipulate her calling device S in accordance with the first digit of the desired number, thereby interrupting the circuit of line relay 102 of connector H a corresponding number of times. Each time the said line relay 102 deenergizes in response to these interruptions it closes at armature 125 the following circuit: From ground by way of armature 125 and its resting contact, armature 127 and its working contact, resting contact of off normal spring 116 and said spring, slow acting series relay 107, and vertical magnet 112 to battery. By the operation of the vertical magnet, the shaft and wipers of the connector H are raised step by step until the latter come to rest opposite the level of contacts in which the line of substation A terminates. The slow acting series relay 107 is maintained energized throughout the series of interruptions and at armature 138 serves to maintain the circuit of the vertical magnet intact after the off normal springs have shifted, as they do upon the first vertical step. As a further result of the energization of relay 107, it places the resistance R^4 in multiple with line relay 104, at armature 137. This is done so as to afford a better impulsive circuit for line relay 102. At the end of the series of interruptions, slow acting relay 107 deenergizes and at armature 137 moves the resistance R^4 from in multiple with line relay 104, and shifts the impulsive circuit from the vertical to the rotary magnet at armature 138.

The operator may now manipulate her calling device in accordance with the second and last digit of the desired number, whereupon line relay 102 is deenergized a corresponding number of times and, upon each deenergization, completes the following circuit: From ground by way of a previously traced circuit to armature 138, and thence by way of the resting contact of the said armature, slow acting series relay 108, resting contact of armature 133 and said armature, resting contact of armature 149 and said armature, and the resting contact of armature 145 and said armature, to battery by way of rotary magnet 113. By the operation of the rotary magnet, the switch shaft and the wipers 161-164, inclusive, are rotated step by step until they finally come to rest upon the desired set of contacts, which in this case are the contacts 165-168, inclusive, being the ones in which the line of substation A terminates. Slow acting series relay 108 is maintained energized throughout the series of interruptions and at armature 139 holds the circuit of stepping relay 110 open, and at armature 140 maintains the circuit of relay 111 open and closes a circuit

for slow acting relay 109. Relay 109, upon energizing, disconnects test wiper 163 from the upper winding of back bridge relay 105 at armature 141 and connects it to the upper winding of switching relay 111, and at armature 142 places the resistance R^4 in multiple with the winding of line relay 104 so as to afford a better impulsing circuit for line relay 102. At the end of the series of interruptions slow acting relay 108 falls back; connects up the test relay 110 at armature 139; closes a point in the circuit of switching relay 111 at the normally closed contacts controlled by armature 140; connects the upper winding of the discriminating relay 106 in series with the release trunk conductor 28 at armature 140; and at the normally open contacts controlled by the said armature opens the circuit of relay 109. Relay 109, being slow acting, maintains its armatures attracted for an interval. A circuit may now be traced from ground, by way of armature 128 of release relay 103, and its working contact, upper winding of discriminating relay 106, release trunk conductor 28, and thence by way of a previously traced circuit to battery by way of switching relay 30 of line switch C'. Discriminating relay 106, upon energizing, closes a locking circuit for itself at armature 135, and prepares a circuit for reversing relay 100 at armature 136.

The above operations take place invariably when a substation is called that is on a line other than that of the calling subscriber, or operator as the case may be. From this point, however, further operation depends upon whether the called line is busy or idle. Assuming now that the line of substation A is busy there is a guarding ground potential on test contact 167 and consequently no current flows through the upper winding of switching relay 111 for the reason that both ends of the said winding are connected to ground and consequently the said relay does not energize. Slow acting relay 109 upon deenergizing, removes resistance R^4 from in multiple with line relay 104 at armature 142, short circuits the upper winding of relay 106 at armature 143, and at armature 141 disconnects the test wiper 163 from the upper winding of switching relay 111 and connects it to the upper winding of the combined busy and back bridge relay 105, by way of the resting contact of armature 131 and said armature. Relay 105, upon energizing, closes the following locking circuit for itself at armature 133 just before its initial circuit is broken at armature 131: From ground by way of the working contact of armature 126 and said armature, lower winding of relay 105, resistance R^3 , working contact of armature 133 and said armature, resting contact of armature 149 and said armature, resting contact of armature 145 and said armature, and rotary magnet 113 to battery. Relay 105 is maintained energized over this circuit but the rotary magnet 113 is not energized on account of the high resistance of R^3 and the lower winding of relay 105. As a further result of the energization of relay 105, it connects a lead from the busy signalling machine to the upper heavy talking conductor by way of armature 132 and its working contact, and the resting contact of armature 146 and said armature. By this operation, the calling operator is given an audible busy signal to inform her that the called line is for the time being inaccessible.

In the present case, however, we may assume that the line of the substation A is idle when called. That being the case, upon the deenergization of slow acting relay 108, the following circuit is closed: From ground, by way of armature 128 and its working contact, normally closed contacts controlled by armature 140, upper winding of switching relay 111, working contact of armature 141 and said armature, normally closed contacts controlled by armature 148, test wiper 163, test contact 167, private normal conductor 174, and the switching relay and stepping magnet of the line switch C, to battery. Switching relay 111 of the connector H and the switching relay of the line switch C are energized in series over the above traced circuit but the stepping magnet of the line switch C is not energized on account of the high resistance of the associated switching relay. The switching relay of line switch C, upon energizing, disconnects the conductors 173 and 175 from battery and ground, respectively, but owing to a mechanical interlocking device (not shown) between the armature of the said switching relay and that of the line relay of the said line switch, the armature of the said switching relay is operated only about half way and consequently the wipers of the line switch are not connected up at this time.

In the connector H, switching relay 111, upon energizing, closes a locking circuit for itself at armature 149 in series with the rotary magnet 113 without, however, operating the said magnet on account of the high resistance of the lower winding of switching relay 111. As a further result of the operation of the said switching relay 111 it connects up the line wipers 161 and 164 at armatures 146 and 150; disconnects the test wiper 162 at armature 147; and at armature 148 places direct ground on test wiper 163, at the same time disconnecting its own upper winding from the said test wiper. Slow acting relay 109 now deenergizes with the hereinbefore mentioned results.

The operator, having finished calling the desired number, now throws her key K to the opposite or ringing position, thereby

operating the springs 9 and 10. Spring 10, upon being operated, disconnects the visual signal 2, while spring 9, upon being operated, inserts the resistance R' into the bridge 5 across conductors 11 and 12. In the connector H, line relay 102, being adjusted relatively stiff, falls back in response to the placing of the resistance R' into the bridge across conductors 11 and 12 but line relay 104, being adjusted relatively light, is maintained energized. Upon deenergizing, line relay 102 completes the following circuit: From ground, by way of armature 125 and its resting contact, armature 127 and its working contact, normally open contacts controlled by off normal spring 116, armature 138 and its resting contact, relay 108, armature 129 and its working contact, armature 117 and its resting contact, ringing relay 101, resting contact of armature 145 and said armature, and rotary magnet 113 to battery. Neither relay 108 nor magnet 113 are energized over the above traced circuit, but ringing relay 101 is energized and at 25 armature 123 maintains the release relay 103 energized, while at armatures 122 and 124 it disconnects the wipers 161 and 164 from the upper and lower windings of back bridge relay 105 and connects them to a source of 30 ringing current, as shown. As long as ringing relay 101 is energized ringing current is sent over the established connection, thereby operating all the bells on the called line.

35 When the operator restores her key K to normal position line relay 102 is energized. Upon energizing, line relay 102 opens the circuit of ringing relay 101 and closes the initial circuit of release relay 103 at armature 125. Upon deenergizing, relay 101 removes the multiple ground from the circuit of release relay 103 at armature 123 and at armatures 122 and 124 disconnects the called line from the source of ringing current and 40 connects up back bridge relay 105 again. The operator may repeat this process until the code of the called substation has been sent out, it being understood of course that each substation is signalled by sending out 45 a different combination of rings. With the key K in normal position, the visual supervisory signal 2, which falls back each time the key K is thrown to ringing position, is operated over its previously traced circuit.

50 When the called subscriber responds by removing his receiver, a direct current bridge is closed across the conductors of the called line, whereupon back bridge relay 105 energizes and at armature 134 completes the following circuit: From ground by way of reversing relay 100, armature 134 and its working contact, working contact of armature 136 of discriminating relay 106, and said armature, working contact of armature 149 55 and said armature, resting contact of armature 145 and said armature, and rotary magnet 113 to battery. Rotary magnet 113 is not energized at this time owing to the high resistance of reversing relay 100 but the latter relay is energized and shifts the control circuit of the ringing relay 101 from the said relay to release relay 103 at armature 117, so that in case the ringing key is operated, either by intent or accident, after the called subscriber has answered, the ringing relay is 60 not operated and the release relay is held up over the ringing relay control circuit. As a further result of the operation of reversing relay 100 it reverses the trunk conductors 27 and 29 at armatures 120 and 121 65 as regards their connection with the line relays 102 and 104 thus causing a reversal of the direction of current flow in the bridge across conductors 11 and 12 in the manual exchange. Polarized relay 5 now retracts 70 its armature owing to the fact that the major path of the magnetic flux extends through the electro magnet and the permanent magnet in series and consequently does not include the armature and heel piece, 75 the said armature being kept from completely touching the iron yoke by the usual brass residual screw (not shown). Upon falling back, the armature of relay 5 opens the circuit of the supervisory signal 2 which de- 80 energizes to give the calling operator answering supervision.

85 Assuming that the jack J is connected with the jack in which the calling line terminates, as has been mentioned before, by 100 means of a cord circuit or by any other suitable means, the two subscribers may now converse with each other, the talking circuits that are shown being outlined by heavy conductors.

105 When the conversation is finished the two subscribers replace their receivers. When the receiver is replaced at substation A the circuit of back bridge relay 105 is opened and the said relay, upon deenergizing, opens 110 the circuit of reversing relay 100 at armature 134. Upon deenergizing, reversing relay 100 reverses the trunk conductors 27 and 29 back to normal, whereupon polarized relay 5 attracts its armature, thereby closing a circuit for the visual supervisory signal 2 which operates to give the operator 115 a disconnect signal.

120 In order to release the connection to substation A, the operator removes the plug from the jack J, thereby connecting up the drop 3 to the tip spring of the jack, at the same time opening the bridge across conductors 11 and 12 at spring 4. The current through the winding of polarized relay 5 now ceases and the magnetic flux emanating from the permanent magnet takes its normal path through the soft iron core, whereupon the armature, which as mentioned hereinbefore is provided with the usual so called 125 130

residual screw, falls back, thereby opening the circuit of supervisory signal 2 which becomes deenergized.

In the connector H, line relays 104 and 102 deenergize in response to the opening of the bridge across conductors 11 and 12. Line relay 102, upon deenergizing, opens the circuit of release relay 103 at armature 125. Release relay 103, upon deenergizing, removes the ground potential from release trunk conductor 28 and private normal conductor 174, and opens the locking circuit of relays 106 and 111 at armature 128, whereupon the said relays deenergize. As a further result of the deenergization of release relay 103, a circuit is closed by way of armature 128 and its resting contact, and off normal contacts 115, for the release magnet 114. By the operation of the release magnet, the shaft and wipers of the connector H are restored to normal position, the circuit of the said release magnet being opened at off normal contacts 115 by the shaft when it reaches normal position. The switching relays of the calling and called line switches obviously deenergize in response to the removal of the ground potential from release trunk conductor 28, and private normal conductor 174. The entire connection, as regards the automatic exchange, is now released.

We shall assume now that the subscriber at substation A desires to call the subscriber at substation A' which is another substation on the same line.

35 When the receiver is removed at substation A, a circuit is closed over line conductors 173 and 175 for the line relay of line switch C and the said line switch C operates in the same manner as the line switch C' did in the previous call to give access to an idle trunk line leading to a connector switch. We shall assume, in this case also, that the connector H is the first one found to be idle and is consequently the one seized.

40 The calling subscriber now manipulates his calling device in accordance with the digits of the desired number, whereupon the connector H operates in exactly the same manner as it did in the previous call until 45 the wipers 161-164, inclusive, are brought into engagement with the contacts 165-168, inclusive, of the called line.

It may be pointed out that while the calling device S' of the substation A is off normal, and consequently while it is interrupting the circuit of line relay 102 of connector H, the resistance R⁶ is included in the bridge across conductors 173 and 175 and brings the resistance of the calling line up to the resistance of the longest line connected in the system.

60 We shall now take up the operation of the connector H at the point where it differs from its operation in the preceding call. At 65 the end of the rotary movement, slow acting

relay 108 deenergizes with the hereinbefore described results, of which one is the inserting of the upper winding of discriminating relay 106 in series with the release trunk conductor 28. Discriminating relay 106, being marginally adjusted, is not energized in this case, however, owing to the fact that it is shunted by the upper winding of switching relay 111 which is at this time connected in series with the switching relay of the line switch C, which is not only the line switch of the called line but also the line switch of the calling line. Switching relay 111, however, owing to the variation of the potential of the release trunk conductor 28 caused by the inserting of the upper winding of relay 106 therein, is able to operate sufficiently to cause armature 148 to make contact with its working contact, thereby closing its previously described locking circuit which causes the said relay 111 to pull all the way up with the hereinbefore described results. As one result of the operation of switching relay 111, direct ground is placed on the test wiper 163 at armature 148, obviously short circuiting the upper winding of discriminating relay 106 completely. As soon as the line wipers 161 and 164 are connected up at armatures 146 and 150, of switching relay 111, back bridge relay 105 energizes over the 95

90 called line, which in this case is the calling line, in series with the bridge across conductors 173 and 175 at substation A. It will be noted that the upper and lower windings of the said relay are in multiple with line relay 104 and line relay 102, respectively, and that, 100 it may be stated, is the principal reason for arranging the connector H so as not to reverse battery when a call, such as the one now being described, is made.

105 The subscriber at substation A may now operate the push button P a number of times corresponding to the number of rings necessary to signal the subscriber at substation A', whereupon line relay 102 of connector H is deenergized a corresponding number of times and upon each deenergization causes ringing current to be sent out as hereinbefore described, thereby ringing the bells at substations A' and A².

110 When the subscriber at substation A' hears his code being set out, he responds by removing his receiver, thereby placing a second direct current bridge across conductors 173 and 175, whereupon the further operation of the ringing push button P becomes 115 obviously ineffective to cause ringing current to be sent out. The calling and called subscribers may now converse with each other, talking current being supplied to the 120 transmitters through the windings of back bridge relay 105 and also through the windings of line relays 104 and 102.

125 When the conversation is finished the two subscribers replace their receivers, where- 130

upon the established connection is released in the manner hereinbefore described.

We shall now assume that the subscriber at substation A² desires to call a subscriber 5 whose line terminates in the manual exchange.

When the receiver is removed at substation A² the line switch C operates in the usual manner to extend the calling line to an 10 idle connector switch and, assuming that the connector H is the one to which the connection is extended, the line and release relays energize in the usual manner thus preparing the switch for operation.

15 The calling subscriber now operates his calling device in accordance with the digits of the desired number, thereby causing the connector H to bring its wipers 161-164, inclusive, into connection with the contacts 20 169-172, inclusive, to which the normal conductors 11, 12 and 13 of the trunk line comprising conductors 11 and 12 are connected.

The sending of impulses from the substation A² is accomplished in the same manner as the sending of impulses from either the substation A or the substation A' with the exception that no resistance is introduced into the bridge across conductors 173 and 175 when the calling device S² is moved 30 from its normal position. Owing to the fact that the line resistance is equal to the resistance of the longest line in the system, any added resistance is unnecessary.

Since there are a plurality of trunk lines, 35 such as the trunk line comprising conductors 11 and 12, any one of which suffice to extend a connection to the manual exchange, the connector H is adapted to automatically rotate in search of an idle one of these trunk 40 lines if the first one of the group happens to be busy. The trunk line comprising conductors 11 and 12 is assumed to be the first one in the group and consequently the two test contacts 170 and 171 are jumpered together. The same is true for the test contacts of the succeeding trunk lines, with the exception that those of the last trunk line 45 in the group are not connected together.

Returning now to the operation of the 50 connector H, it will be taken up at a point where it differs from that already explained. At the end of the rotary movement slow acting relay 108 falls back followed by the energization of the discriminating relay 106 which energizes in series with the switching relay of the calling line switch 55 in a manner hereinbefore described. From this point the operation depends upon whether the trunk line comprising conductors 11 and 13 is busy or idle. Assuming 60 that it is busy, there is a ground potential on test contact 170 and stepping relay 110 energizes immediately after armature 139 falls back, over the following circuit. From 65 ground by way of test contact 170, test

wiper 162, resting contact of armature 147 and the said armature, resting contact of armature 139 and said armature, resting contact of the armature of rotary magnet 113 and the said armature, and stepping relay 110 to battery. Upon energizing, stepping relay 110 closes a circuit for slow acting relay 109 at armature 144 before the said relay has fallen back, and at armature 145 closes the following circuit for rotary 70 magnet 113: From ground by way of armature 128 and its working contact, normally closed contacts controlled by armature 140, working contact of armature 145 and the said armature, and rotary magnet 113 to 80 battery. Upon energizing, rotary magnet 113 advances the wipers 161-164, inclusive, into engagement with the contacts of the next trunk line, at the same time opening the circuit of stepping relay 110; upon de-energizing, stepping relay 110 opens the circuit of slow acting relay 109 at armature 144, and at armature 145 opens the circuit of rotary magnet 113 which deenergizes and 85 closes a point in the circuit of stepping relay 110. This process is repeated over and over as long as the wipers of the connector engage contacts of a busy trunk line, but if all the trunk lines of the group are busy, when the last one is reached, or the one that does not have a jumper between its test contacts, there is no circuit closed for the stepping relay and consequently the rotary 90 movement ceases. With this condition existing slow acting relay 109 finally falls back, and at armature 141 disconnects the test wiper 163 from the winding of switching relay 111 and connects it to the upper winding of the combined back bridge and busy relay 105 with the final result that a 95 busy signal is sent back to the calling subscriber in the same manner as has been described hereinbefore, when the operator was calling.

In the present case however, we shall assume that the trunk line terminating in bank contacts 169-172, inclusive, is idle when the call is made as described. Such being the case, when the wipers 161-164, inclusive, of the connector H arrive on the 110 set of contacts of the said idle trunk line, there is no operative circuit closed for the stepping relay 110 (the resistance of the upper winding of switching relay 111 being high enough to prevent the said stepping relay 110 from energizing in series with it) and switching relay 111 energizes in the usual manner; opens the circuit of the rotary magnet 113 and closes a locking circuit for itself at armature 149; opens the circuit of stepping relay 110 at armature 147; grounds the test wiper 163 at armature 148; and at armature 146 and 150 connects up the line wipers 161 and 164.

In response to the placing of ground on 130

test wiper 163, switching relay 30 of line switch C' is energized over private normal conductor 13 and at armatures 16 and 18 clears the called trunk line of its normal battery and ground connections.

The calling subscriber may now operate his push button momentarily, thereby causing the connector H to send ringing current out over the established connection to operate the drop 3. When the operator in the manual exchange responds by inserting a plug in the jack J, the drop 3 is cut off and the before described bridge is placed across the conductors 11 and 12. The polarized relay 5, however, included in the said bridge, is not operated at this time, owing to the fact that the normal conductors of the trunk line are reversed at the banks of connector H, thus sending a current through the said polarized relay in a direction opposite to that in which it must flow to operate the said relay. The calling subscriber and the operator now converse with each other in the usual manner and the operator may extend the connection to the desired subscriber in any well known or approved way.

After the conversation is finished the subscriber at substation A² replaces his receiver, whereupon the connector H restores itself to normal position in the usual manner. As soon as the ground potential is removed from the private normal conductor 12 switching relay 30 of the line switch C' de-energizes and again connects up line relay 14 which energizes over the bridge across conductors 11 and 12 in the manual exchange and is operated in the usual manner to pick out an idle trunk line, whereupon the polarized relay 5 is energized and closes a circuit for the visual supervisory signal 2 which becomes operated to give the operator a disconnect signal.

When the operator removes the plug from the jack J, supervisory signal 2, polarized relay 5, line switch C', and the connector to which the connection has been extended, assume normal position in the usual manner.

Having described and ascertained the features of the invention, what is considered to be new and desired to be protected by the Letters Patent will be pointed out in the appended claims.

What I claim as my invention is:

1. In an automatic telephone system including party lines, a connector switch for connecting a calling and a called line, means in said connector for reversing the direction of current flow in the calling line, and means for preventing such reversal in case the calling and called lines are the same.

2. In an automatic telephone system including party lines, a connector switch for connecting calling and called lines, means in said connector for reversing the direction of current flow in the calling line when the

subscriber on the called line answers, and means for preventing such reversal in case the calling and called subscribers are both on the same line.

3. In an automatic telephone system including party lines, a connector switch controlled from a calling station to extend a connection to a called station, means in said connector for reversing the talking battery supply connections of said calling station when the subscriber at the said called station answers, and means for preventing such reversal in case the said called station is on the same party line with the said calling station.

4. In an automatic telephone system including party lines, an automatic connector switch for connecting calling and called lines, a reversing relay in said connector adapted to reverse the direction of current flow in any calling line connected to such connector, circuit connections for energizing said relay in case the calling and called stations are not on the same line, and other circuit connections for preventing the energization of said relay in case the calling and called stations are on the same line.

5. In an automatic telephone system including party lines, an automatic connector switch for connecting calling and called lines, a reversing relay in said connector adapted to reverse the direction of current flow in any calling line connected to such connector, circuit connections for energizing said relay in case the calling and called stations are not on the same line, a discriminating relay for rendering said circuit connections effective, and circuit arrangements for preventing the energization of said discriminating relay in case the calling and called stations are on the same line.

6. In a telephone system, main and branch exchanges, party lines in the branch exchange terminating in individual line switches, trunk lines extending from the main exchange to the branch exchange and also terminating in individual line switches, connector switches in the branch exchange accessible to all said line switches in common, said connectors being controllable either by an operator in the main exchange or by calling subscribers in the branch exchange to connect with branch exchange lines, suitable circuit arrangements in said connectors whereby any calling party line subscriber in the branch exchange can call another party on the same line, and reversing relays in said connectors for reversing the direction of current flow in the said trunk lines when the connectors are used in main to branch exchange connections in order to give supervision to the main exchange operator.

7. In an automatic telephone system, subscribers' lines, automatic switches for con-

necting said lines, calling devices at the stations on said lines for controlling said switches, resistances at the said stations normally excluded from the line circuits, and a 5 switching device controlled by each calling device when the same is operated for inserting the associated resistance in the line circuit.

8. In an automatic telephone system, subscribers' lines, automatic switches for connecting said lines, calling devices at the stations on said lines for controlling said switches, a resistance at each of said stations, each resistance having a value such 10 that when added to the resistance of the associated line the total line resistance will approximate the line resistance of the longest line in the system, said resistances being normally out of circuit, and a switching device controlled by each calling device for inserting the associated resistance in the line circuit when the calling device is operated.

9. In an automatic telephone system including party lines, a connector switch for 25 connecting a calling and a called line, means in said connector for reversing the current flow in the calling line, and means for preventing the operation of said reversing means in case the calling and called 30 lines are the same.

10. In a telephone system including party lines, an automatic connector switch controllable over a calling party line to complete a connection to the calling line or 35 to another line, a signal controlling device at the calling station, signalling equipment in said connector controllable by said device to signal the desired station, means in said connector controlled through the direct current talking bridge at the called station for rendering said signalling equipment unresponsive to said device, and means for rendering the operation of the 40 last named means ineffective when the called station is on the calling line.

11. In an automatic telephone system, a party line, other lines, an automatic switch controlled from a calling station on said party line for connecting said party line 45 with any one of said other lines, and an artificial resistance at each of certain ones of the stations of said party line, each of said resistances being of a value such that when it is added to the resistance of the portion of line between the associated station and the exchange the total resistance approximates a definite value determined by the length of the longest line of the system.

12. In an automatic telephone system including party lines, a connector switch for connecting a calling and a called line, and means in said connector switch for reversing the current flow in the calling line only 50 in case the calling line is not also the called line.

13. In an automatic telephone system including party lines, a connector switch for connecting a calling and a called line, a reversing relay in said connector switch for reversing the current flow in the calling 70 line, and circuit arrangements for operating said reversing relay to make such reversal only in case the calling line is not also the called line.

14. In an automatic telephone system, 75 lines, certain of said lines being party lines, a connector switch for connecting a calling and a called one of said lines, a relay in said switch for reversing the current flow in a calling line, and a discriminating relay 80 in said switch for preventing the operation of said reversing relay if the calling and the called parties are on the same line.

15. In an automatic telephone system, 85 party lines, other lines, switches for establishing connections between said lines, each station on said lines equipped with a calling device for controlling said switches, a resistance at each of certain ones of the stations on said lines for changing the resistance of the associated line to approximate the resistance of the longest line in the system, said resistances being normally out of 90 circuit, and means for inserting the associated resistance in the line circuit only 95 during the operation of the calling device.

16. In a party-line telephone system, a connector switch responsive to a control over a calling line to complete a connection to a called line, and responsive to control 100 from said called line when the latter is a calling line for completing a connection to said called line, the control exercised over said connector being the same in both cases, a relay included in said connector, and 105 means for operating said relay incidental to only one of said connections.

17. In a party-line telephone system, a connector switch responsive to a control over a calling line to complete a connection 110 to a called line, and responsive to control from said called line when the latter is a calling line for completing a connection to said called line, the control exercised over said connector being the same in both cases, 115 and means included in said connector for discriminating between said connections.

18. In a party-line telephone system, a connector switch controlled over any calling line to set up a connection to another called 120 line and to set up a connection to the said calling line as a called line, and means automatically operated by said connector to discriminate between said connections, said connector being subjected to the same external control in each case.

19. In a party-line telephone system, a connector switch controlled over any calling line to set up a connection to another called 125 line and to set up a connection to the said 130

calling line as a called line, a supervisory control device included in said connector and operated incidental to only one of said connections, and a supervisory device outside of said connector and under the control of said supervisory controlling device.

20. In a party-line telephone system, a connector switch controlled over any calling line to set up a connection to another called line and to set up a connection to the said calling line as a called line, a supervisory controlling relay in said connector automatically operated incidental to only one of said connections, and a supervisory device outside of said connector and under the control of said supervisory relay.

21. In a party line telephone system, a connector switch, a pair of talking conductors and a release trunk conductor incoming to said switch, means for controlling said switch over any calling line and over one of said incoming talking conductors to set up a connection to another called line and to set up a connection to the said calling line as a called line, and means automatically operated by said connector over said release trunk conductor to discriminate between said connections.

22. In a party line telephone system, a connector switch, a pair of talking conductors and a release trunk conductor incoming to said switch, talking wipers and a test wiper for said switch, means for controlling said connector switch over any calling line and over one of said incoming talking conductors to set up a connection to another called line and to set up a connection to the said calling line as a called line, said connections including said incoming conductors and said wipers, and means automatically operated by said connector and controlled jointly over the incoming release trunk conductor and said test wiper to discriminate between said connections.

tors and a release trunk conductor incoming to said switch, talking wipers and a test wiper for said switch, means for controlling said connector switch over any calling line and over one of said incoming talking conductors to set up a connection to another called line and to set up a connection to the said calling line as a called line, said connections including said incoming conductors and said wipers, and means automatically operated by said connector and controlled jointly over the incoming release trunk conductor and said test wiper to discriminate between said connections.

23. In a party line telephone system, a connector switch controlled over any calling line to set up a connection to another called line and to set up a connection to said calling line as a called line, a discriminating relay in said connector, means for operating said relay when the connector completes a connection to a line other than the calling line, and circuit connections for preventing the operation of said discriminating relay when the connector completes a connection to the calling line.

In witness whereof, I hereunto subscribe my name this 30th day of June, A. D. 1921.

JOHN I. BELLAMY.
